UNITED STATES PATENT OFFICE

153,828

DESIGN FOR A FOLDING JEWEL CHEST

Charles C. Settle, Columbus, Ind.

Application October 13, 1947, Serial No. 141,886

Term of patent 3½ years

(Cl. D86—9)

To all whom it may concern:

Be it known that I, Charles C. Settle, a citizen of the United States, residing at Columbus, in the county of Bartholomew and State of Indiana, have invented a new, original, and ornamental Design for a Folding Jewel Chest, of which the following is a specification, reference being had to the accompanying drawing, forming part thereof.

Figure 1 is a perspective view of a folding jewel chest, showing my new design and illustrating the same in a folded position, and

Figure 2 is a perspective view thereof, illustrating the same in a partially open position with one cover removed.

I claim:

The ornamental design for a folding jewel chest, as shown.

CHARLES C. SETTLE.
